ROTARY IMPACT, RATCHET-TYPE WRENCH

Richard Plews Potter, Kew, Victoria, Australia, assignor to Maurice Ravdell, Misha Ravdell, and Leonard Maurice Stanton, all of Melbourne, Victoria, Australia

Application May 27, 1957, Serial No. 661,687

5 Claims. (Cl. 81—52.3)

This invention relates to shock wrenches for the loosening and complete removal of nuts, studs or bolts which through adhesion caused by corrosion, damaged threads, expansion and contraction due to temperature changes, overtightening, or chemical action cannot be removed by ordinary spanners or wrenches operating on manually applied leverage principles.

It is customary in practice to loosen or endeavour to loosen an overtight or firmly adhering nut, by striking a spanner applied to the nut or by the use of a punch or the like applied to the corners of the nut and struck with a hammer. Such methods even if effective are not satisfactory in that the spanner or the nut or both are apt to be damaged.

Now the principal object of this invention is to provide a simple, efficient and durable device which is convenient and easy to use, very effective for loosening an overtight or adhering nut or the like, and can be manufactured at relatively low cost.

A further object is the provision of a device of the type referred to, which, after it has been used to break the adhesion between a screw-threaded member and an overtight or firmly adhering nut, may then be used more or less in the manner of a known type of ratchet wrench to complete the unscrewing of the nut from the threaded member.

Another object is to provide a device of the type referred to, which can be used for the loosening or tightening of nuts or the like of all normal sizes and with nuts or the like having either a right or left hand thread.

Although the novel features which are believed to be characteristic of this invention will be more particularly pointed out in the claims appended hereto, the invention itself may be better understood by referring to the following description, taken in conjunction with the accompanying drawings, in which a specific embodiment thereof has been set forth for purposes of illustration. In these drawings:

Figure 1 is an exploded perspective view of one form of shock wrench in accordance with the invention;

Figure 2 is a sectional view on an enlarged scale through a portion of the device shown in Figure 1;

Figure 3 is a sectional view taken on the line 3—3 in Figure 2;

Figure 4 is a perspective view of a part of the device and

Figure 5 is a side elevation of a portion of a modified form of device according to the invention, parts thereof being broken away.

As shown in Figures 1 to 4 of the drawings, the shock wrench is provided with an impact shaft 10 which is hollowed at both ends. The openings in the ends of the shaft comprise cylindrical outer portions 11, 12, square-sectioned central portions 13, 14 and cylindrical inner portions 15, 16. The outer cylindrical portions 11, 12 and the central portions 13, 14 are of such a size as to neatly

2

accommodate part of the cylindrical central portion 17 and a square-sectioned end portion 18 of a socket spanner adapter indicated generally by the reference 19. The cylindrical inner portions 15, 16 are of such a size as to neatly accommodate the reduced end portion of a stabilizing bar 20 which is inserted into the openings in one end of the impact shaft during use of the device. The outer end of the stabilizing bar 20 is fitted with a curved holding plate 21 to enable the operator to exert a force 10 along the axis of the impact shaft to enable the operator to hold the tool in position during use.

The impact shaft is rotatably mounted within a hollow cast steel housing 22 having a removable end plate 23 which is bolted in place after the insertion of the impact shaft into the housing. The latter also carries an elongated hollow boss 24 to which a long handle 25 is rigidly and removably connected as, for example, by means of a pin 26. The handle 25 is weighted at the outer end and is fitted with a sponge rubber or otherwise cushioned hand grip 27.

In the centre of the impact shaft are four cam-like projections comprising radially sloping shoulders 28 disposed at 90° intervals around the shaft, and connected by gently sloping curved surfaces 29, the projections being 25 formed integrally with or rigidly connected to the shaft. The projections are disposed within the housing 22 which is shaped to fit neatly around them while allowing rotation of the shaft and projections in the housing. Disposed within the elongated hollow boss 24 is a pawl 30 which 30 is urged radially towards the centre of the impact shaft by a compression spring 31 so that it normally rides on one of the curved surfaces 29. The pawl 30 is provided one one side with a flat vertical face 32 (as seen in Figure 2) which is adapted to engage and co-act with the shoulders 28 as hereinafter described, while the base of the opposite side of the pawl is sloped as at 33 (Figure 3) for a purpose referred to hereinafter.

The adapter 19, besides having a cylindrical portion 17 and a square-sectioned portion 18 at one end as previously described, also has a square-sectioned portion 38 at its other end which is adapted to fit into any of the head pieces 34 of a standard socket spanner.

In use of the device, say to unscrew a nut which cannot be moved by means of normal hand operated spanners or wrenches, the appropriate size socket spanner head piece is placed on the nut and the adapter 19 inserted into the head piece. The appropriate end of the hollow impact shaft is then engaged with the free end 18 of the adapter and the reduced end of the stabilizing bar inserted into the opposite end of the impact shaft.

The device thus being assembled, pressure is applied along the stabilizing bar to retain the socket spanner head piece 34 in engagement with the nut while the operator swings the handle back through any portion of 90° 55 and then drives it forward so as to bring the pawl 30 into sharp impacting engagement with a shoulder 28 on one of the projections of the impact shaft. This causes a sudden strong force to be applied to the nut in a manner tending to rotate the same, and therefore, after one or more applications, will break adhesions or other conditions impeding the removal of the nut. As the rear side of the lower end of the pawl 30 is sloped as at 33 to provide only an edge contact between the pawl and the curved surfaces of the cam-like projections, the pawl is maintained in a 60 position such that the flat face 32 is always directed towards the shoulder 28 with which the pawl comes into contact so that a full face-to-face engagement between the pawl and the shoulder is obtained. After delivering the impact, the handle is merely returned to its original position and again swung forward until the pawl engages the shoulder thereby applying a further jarring impact tend-

ing to rotate the nut. Obviously the speed at which the pawl is travelling when it comes into contact with the shoulder is one factor determining the magnitude of the force applied to the nut and the fact that the handle has a wide free angle of movement (in this case up to 90°) is one of the reasons for the surprising effectiveness of the present device as compared with known types of ratchet wrenches or the like.

When a nut has remained for a long time on a bolt, crystal growths cementing the nut to the bolt commonly arise and these are often more resistant to normal leverage as applied by known ratchet wrenches or the like than the bolt itself so that the application of leverage in known manner often results in shearing of the bolt. On the other hand, it has been found that the application of shocks or jarring impacts to the nut by means of the present device is surprisingly effective in shattering the aforesaid crystal adhesions with the result that shearing of the bolt does not normally occur. Also, it may readily be appreciated that the pawl and cam-like projections of the present device are adapted to transmit shocks or jarring impacts whereas the corresponding parts in a normal ratchet wrench are not so adapted and are only suitable for the transmission of a steady leverage.

After having loosened the nut by the application of the requisite number of impacts in the manner described, the handle can be pulled back through an angle sufficient to cause the spring-loaded pawl to ride over the edge of the sloping surface 29 with which it happens to be in contact and to drop into engagement with the next shoulder 28, thereby permitting the tool to be used thereafter if desired somewhat in the same manner as a known type of ratchet wrench. Should further tight sections be encountered however, the "shock" or "impact" method of operation may be reintroduced until complete removal is effected.

If it is necessary to use the device in a restricted space, the normal handle may be removed and replaced by a shorter handle. On the other hand, if a longer handle is desired, such may be fitted in place of the normal handle or the cushioned hand grip 27 may be removed in order to allow the insertion of an extra handle into the interior of the normal handle so as to increase the effective handle length. Alternatively the extra handle may be fitted exteriorly over the existing handle. Also, adjustment of the position of the working arc of the handle may be achieved readily merely by rotating the head piece 34 to the appropriate position before engaging it with the nut.

From the above description, it will be obvious that the tool can be used for the loosening or tightening of nuts, studs, bolts or the like having either left or right handed threads by turning the housing in the appropriate direction before engaging the impact shaft with the adapter, bearing in mind the orientation of the shoulders on the projections on the impact shaft and the direction in which the nut or the like is to be turned.

In the device described above, the impact shaft is provided with four cam-like projections, but it is obvious that this number may be varied according to circumstances. For instance the number of projections may be reduced to three, while in some cases it may be convenient to increase the number to say six. Of course the greater the number of projections present, the less is the free angle of movement of the handle and for normal usage, four projections providing a free angle of movement of 90° are preferred.

In the modification illustrated in Figure 5, the impact shaft, instead of being hollowed at its ends as in Figures 1 to 4, is provided with square or hexagonal studs 35 which project from its ends and are adapted to engage with expanded hollow ends 36, 37 of an adapter and stabilizing shaft respectively. This construction has the advantage that it avoids the provision of intermediate non-circular portions as at 13, 14 of the hollowed end sections.

of the impact shaft described in relation to Figures 1 to 4.

This invention thus provides a device which permits the removal of nuts, studs or bolts that would be difficult or impossible to remove by ordinary means, and moreover, the removal is effected without damage such as occurs with the use of oxy-acetylene torches, hammers, chisels and the like. The force applied is completely at the control of the operator and complete removal can be effected without re-positioning the tool. The device is readily portable and requires no electric, pneumatic or hydraulic sources of power and retains its efficiency in use as there are no springs or similar parts liable to fatigue.

I claim:

1. A shock wrench comprising a housing, an impact shaft rotatably mounted within said housing, an impact receiving member rigidly secured to said shaft, said impact receiving member comprising a series of steeply sloping abutment faces directed transversely of the axis of said shaft each of which is connected to an adjoining face by a gently rising surface extending from the base of one face to the top of the adjoining face, an impact transmitting member mounted in said housing, spring means adapted to urge said impact transmitting member in a direction towards said impact receiving member, the impact transmitting member being provided with a face adapted to engage one of the said steeply sloping abutment faces on rotation of the said housing in one direction relatively to said shaft, the impact transmitting member being shaped to provide only an edge contact with said gently rising surfaces under the influence of said spring means to ensure a full face-to-face engagement between the said face of the impact transmitting member and one of the said steeply sloping abutment faces on rotation of said housing relatively to said shaft, means connecting said shaft non-rotatably with a nut, stud or bolt, and an elongated handle secured to said housing, whereby a sudden shock loading tending to rotate said nut, stud or bolt may be delivered through said shaft by the engagement of the impact transmitting member with one of the steeply sloping impact faces of said impact receiving member, the said impact transmitting member and the said impact receiving member being adapted to transmit a sudden shock loading to the nut, stud or bolt after a free swinging movement of the handle and the said gently rising surfaces on the impact receiving member being such as to allow the impact receiving member and the impact transmitting member to rotate relatively to each other, whereby the impact transmitting member can pass over one of the said gently rising surfaces from a position at the base of one of the steeply sloping abutment faces to the base of an adjoining steeply sloping abutment face.

2. A shock wrench comprising a housing, an impact shaft rotatably mounted within said housing, an impact receiving member rigidly secured to said shaft, a series of steeply sloping abutment faces on the impact receiving member and directed transversely of the axis of said shaft, each of the steeply sloping abutment faces on the impact receiving member being connected to an adjoining abutment face by a gently rising surface extending from the base of one abutment face to the top of the adjoining face, an impact transmitting member mounted in said housing, spring means normally maintaining said impact transmitting member in contact with one of the said gently rising surfaces on said impact receiving member, the impact transmitting member being provided with a face adapted to be brought into shock delivering engagement with a said abutment face, means connecting said impact shaft non-rotatably with a nut, stud or bolt, and a handle secured to said housing, whereby a sudden shock loading tending to rotate said nut, stud or bolt may be delivered through said impact shaft by swinging said handle through an appreciable angle to bring the said face of the impact transmitting member into shock delivering engagement with a steeply sloping abutment face of said

impact receiving member, the said gently rising surfaces of the impact receiving member being such as to allow the impact receiving member and the impact transmitting member to rotate relatively to each other, whereby the impact transmitting member can pass over one of the said gently rising surfaces from a position at the base of one of the steeply sloping abutment faces to the base of an adjoining steeply sloping face.

3. A shock wrench as claimed in claim 2, and further comprising a stabilizing bar connected to the impact shaft, whereby pressure may be directed along the axis of said impact shaft to maintain the device in engagement during use with the nut, stud or bolt.

4. A shock wrench as claimed in claim 2, in which the impact shaft is hollow at least at one end and the means connecting the impact shaft with a nut, stud or bolt comprises a socket spanner adapter adapted to fit non-rotatably into the said hollow end of the impact shaft and a socket spanner head piece adapted to be non-rotatably connected to the adapter.

5

5. A shock wrench as claimed in claim 2, in which the impact shaft is provided at one end with a projection and the means connecting the impact shaft with a nut, stud or bolt comprises a socket spanner adapter adapted to fit non-rotatably onto the said projection and a socket spanner head piece adapted to be non-rotatably connected to the adapter.
